Term of patent 14 years

(Cl. D48—32)

FIG. 1.

FIG. 2.

FIG. 3.

FIG. 4.

FIG. 1 is a front perspective view of a roof light housing for automotive vehicles and the like showing my new design;

FIG. 2 is a perspective of the roof light housing for automotive vehicles and the like showing my new design, this view being taken at a different angle than that of FIG. 1;

FIG. 3 is a top plan view thereof; and

FIG. 4 is an end elevation thereof.

The shading indicates translucent plastic material.

The characteristic feature of my design resides in the specific configuration of the upwardly projecting lens member in combination with the conventional flat flange as shown.

I claim:

The ornamental design for a roof light housing for automotive vehicles and the like, as shown and described.
